UNITED STATES PATENT OFFICE

156,667

CLOWN DOLL

Joseph Rubin, Brooklyn, N. Y.

Application June 25, 1948, Serial No. 147,189

Term of patent 3½ years

(Cl. D34—4)

To all whom it may concern:

Be it known that I, Joseph Rubin, a citizen of the United States, residing at Brooklyn, in the county of Kings and State of New York, have invented a new, original, and ornamental Design for a Clown Doll, of which the following is a specification, reference being had to the accompanying drawings, forming a part thereof.

In the drawings:

Fig. 1 is a side view of a clown doll, showing my new design;

Fig. 2 is a front view thereof.

I claim:

The ornamental design for a clown doll, as shown.

JOSEPH RUBIN.
